UNITED STATES PATENT OFFICE.

JEAN HENRI LABOURDETTE, OF COURBEVOIE, FRANCE.

DESIGN FOR A TRAILER FOR AUTOMOBILE VEHICLES.

58,917.

Specification for Design.

Patented Sept. 6, 1921.

Application filed July 30, 1920. Serial No. 400,239. Term of patent 14 years.

To all whom it may concern:

Be it known that I, JEAN HENRI LABOURDETTE, a citizen of the French Republic, and residing at Courbevoie, in the Department of Seine, and State of France, have invented a new, original, and ornamental Design for Trailers for Automobile Vehicles, of which the following is a specification, reference being had to the accompanying drawing, forming part thereof.

Fig. 2, being a rear end view, and
Fig. 3 a front end view in perspective.

I claim:

The ornamental design for a trailer for automobile vehicles, as shown.

In testimony whereof I affix my signature, in presence of two witnesses.

JEAN HENRI LABOURDETTE.

Witnesses:

CAÏUS DANZER,
LUCIEN CRESPIN.
